PROPELLION MEANS FOR BOATS

John Napoli, Monterey, Calif.

Application June 7, 1949, Serial No. 97,602

3 Claims. (Cl. 114—0.5)

1

This invention relates to an improved system for propelling marine vessels, and more particularly to a novel combination by which electrical energy may be generated while a vessel is being propelled through the water or while it is at anchor.

The present invention provides an improved propulsion system for marine vessels which is adapted to operate an electrical generating plant as the vessel is propelled forwardly through the water, or while it is at anchor or tied up at a dock, thereby generating electrical energy for use in and about the vessel. The propulsion system embodies an electricity generating rotor having circularly arranged peripheral grooves against the sides of which water under pressure is directed as the vessel is propelled forwardly or against which a stream of water from a nozzle is directed by means of a pump while the vessel is at anchor. Suitable controls are provided for selectively controlling the flow of water under pressure against the rotor.

The present invention is a continuation in part of the invention disclosed in my Patent No. 2,456,834, granted December 21, 1948, for improvements in propulsion means for boats.

In the accompanying drawings:

Fig. 1 is a side elevation of a part of a boat, showing diagrammatically an electrical generating plant embodying the preferred principles of my invention;

Fig. 2 is a vertical section taken longitudinally through the rotor;

Fig. 3 is a bottom view of the rotor; and

Fig. 4 is a sectional view taken on the line 4—4 of Fig. 2.

Referring to the drawings, the numeral 1 designates the keel portion of a marine vessel or other type of boat, 2 the hull, 3 the propeller which is suitably connected to a source of power such as an electrical motor or an internal combustion engine, and 4 the rudder.

The keel portion of the boat is provided with a suitably shaped slotted opening 5 over which is positioned and secured a housing 6 having axial bearings 6' within which is rotatably supported a shaft 7 which is provided at one end with a pulley 8. Keyed to the shaft 7 is a rotor 9 which has discs 10 of substantially the same maximum diameter secured to its opposite sides. The discs 10 may be eliminated if so desired by having the opposite sides of the housing 6 arranged in close relationship with respect to the sides of the rotor. The rotor is provided at its periphery with a number of spaced projections

2

or teeth 9' which are uniformly spaced one from the other and which are so shaped as to form spaced open grooves or pockets 9a. The discs 10 enclose the sides of the pockets or grooves. The rotor 9 may be formed with a greater or less number of peripheral teeth and grooves than shown on the drawings, but for all practical purposes satisfactory results may be obtained by providing twelve or sixteen, or as many as thirty-two, spaced projections and grooves at the periphery of the rotor.

Secured to and extending below the keel 1 and positioned at opposite sides of the opening 5 are longitudinally disposed spaced members 11 which provide a channel therebetween. Secured to the keel 1 and arranged in a depending position beneath the lower projecting portion of the rotor 9 is an enclosure 11' having an opening at its forward end which is controlled by a valve 12. The valve 12 is secured to a screw 13 which extends through and operatively engages with threaded openings in stationary bearing members 14. A hand wheel 15 secured to the screw 13 and operable from the interior of the vessel provides means for operating the valve to open and close the forward opening in the enclosure 11'. The enclosure 11' has a rear opening as at 16. Suitably supported longitudinally beneath the keel 1 is a tubular member 17 having its inlet end flared and positioned inside the enclosure 11' adjacent the periphery of the lower rear portion of the rotor 9. The exhaust or rear end of the tubular member 17 is positioned rearwardly of the enclosure, and associated with the said tubular member is a valve housing 18 within which a valve (not shown) is mounted, the said valve being operable by a hand control wheel 19 from inside the vessel. The valve which is positioned in the valve housing 18 may be opened or closed by the operation of the hand control wheel 19 to control the flow of water through the rear portion of the tubular member 17.

A suitable opening 20 in the keel 1 at a point rearwardly of the large opening 5 allows water to enter a chamber 20' in the lower rear portion of the housing 6. Connected to the chamber 20' is a tubular connection 21 leading to a collector 22' which in turn is connected to the intake side of a pump 22, the said pump being operated by a suitable electric motor or an internal combustion engine (not shown). A control valve (not shown) operable by a hand wheel 23 from the interior of the vessel is positioned in the tubular connection 21. Connected to the collector 22' is a conduit 24 which is also connected to the tubular

member 17. A control valve located as at 25 in the conduit 24 and operable by a hand wheel is arranged to control water flowing from the tubular member 17 to the collector 22.

Arranged in a position for discharging a stream of water tangentially against the rotor 9 is a nozzle 26 which is connected by a conduit 27 to the outlet or discharge side of the pump 22. A valve (not shown) positioned as at 28 in the conduit 27 and controlled by a hand wheel 29 is adapted to control the flow of water from the pump to the nozzle 26. A discharge pipe 30, connected to the discharge side of the pump 22 is provided as at 31 with a valve for allowing the water from the pump to be discharged from the vessel or to be directed upwardly through the conduit 27.

The pulley 8 secured to the rotor shaft 7 is connected by an endless belt 32 to an electric generator 33, and the latter is connected electrically by suitable wires to a storage battery 34. The electrical energy produced by the generator 33 is stored in the battery 34 and through outlet wires it may be supplied to any device or mechanism on the boat which is to be electrically operated.

In the normal operation of the system when the vessel is proceeding forwardly the valves 12 and 18 are open, thereby allowing water under pressure to enter the enclosure 11 and tangentially impinge against the lower peripheral projections 9' of the rotor 9. The valves at 23, 25 and 31 are then closed and the pump 22 is not in operation. The pressure of the water against the lower part of the rotor's periphery turns the said rotor and thereby causes the electric generator to operate to produce electrical energy. In instances when the vessel is not traveling forwardly with sufficient speed to cause the rotor 9 to operate, it is desirable to utilize the pump 22 for the operation of the rotor. In one of such instances the valve at 18 controlling the flow through the tubular member 17 is closed and the valves at 25 and 28 are opened. The water is then drawn from the tubular member 17 by the pump 22 and directed with pressure through the conduit 27 to and from the nozzle 26 against the periphery of the rotor, thereby causing the latter's rotation. When the vessel is docked, as when the cargo loading operation is in progress, the valves at 12, 18, 25 and 31 are closed while the valve at 23 is open. The water is drawn from the chamber 20 by the pump 22 and discharged from the nozzle 26 with sufficient pressure to cause the rotation of the rotor 9. It is also possible to cause the rotor to slowly operate through the suction created by the pump 22 when the valves at 18, 23, and 28 are closed and the valves at 12, 25 and 31 are open. In such an instance the water drawn into the enclosure 11 through the forward opening in the latter is circulated through the conduit 24, the pump 22 and discharged through the pipe 30. In instances where the maximum power is to be generated by the

system, the valves at 12, 25 and 28 are open while the valves at 18, 23 and 31 are closed. The pump 22 draws the water from the tubular member 17 thereby creating a suction which exerts an added pressure upon the rotor 9 in addition to that caused by the forward movement of the vessel. The pump discharges the water thus drawn from the tubular member 17 through the nozzle 26, thereby giving increased impetus to the rotation of the rotor.

What I claim is:

1. In a boat having a keel provided with an opening, a housing mounted on the keel above the opening therein, a shaft rotatably supported by the housing, a rotor keyed to the shaft and having peripheral teeth, the said rotor being arranged with a portion thereof projecting beneath through the opening in the keel, an enclosure secured beneath the keel and arranged beneath and at the opposite sides of that portion of the rotor which projects through the opening in the keel, the said enclosure having water inlet means at its forward end and water outlet means at its rear end, a pump connected at its intake end to the water outlet means, a nozzle arranged to direct water tangentially against the teeth of the rotor, and a conduit connecting the discharge end of the pump with the nozzle.
2. In a boat, the combination defined by claim 1 together with an electric generator connected to the shaft.
3. In a boat having a keel provided with a longitudinal opening, a housing mounted on the keel above the opening, a rotor rotatably supported in the housing and arranged with a portion thereof projecting through the opening in the keel and beneath the latter, the said rotor having spaced peripheral teeth, an enclosure secured to the keel and arranged longitudinally and in an enclosed position with respect to that portion of the rotor which projects beneath the keel, the said enclosure having water inlet means at its forward end and water outlet means at its rear end, control valves associated with the inlet and outlet means, a pump connected at its inlet end to the outlet means, a nozzle arranged to direct a stream of water tangentially against the rotor, and a conduit connecting the discharge end of the pump and the nozzle.
